(57) **CLAIM**

The ornamental design for a toolbox, as shown and described.

DESCRIPTION

FIG. 1 is a front perspective view of a design for a toolbox; FIG. 2 is a front elevational view of the design as seen in FIG. 1;

FIG. 3 is a rear elevational view of the design as seen in FIG. 1;

FIG. 4 is a right side elevational view of the design as seen in FIG. 1;

FIG. 5 is a left side elevational view of the design as seen in FIG. 1;

FIG. 6 is a top plan view of the design as seen in FIG. 1; and, FIG. 7 is a bottom plan view of the design as seen in FIG. 1.

The broken lines shown in the drawings illustrate portions of the toolbox and form no part of the claimed design.

1 Claim, 7 Drawing Sheets(56)
